UNITED STATES PATENT OFFICE

115,504

DESIGN FOR A COMBINED STORAGE AND DISPENSING CABINET

Jacques Martial, New York, N. Y., assignor to Charles Q. Sherman, Mount Vernon, N. Y.

Application March 28, 1939, Serial No. 83,870

Term of patent 7 years

To all whom it may concern:

Be it known that I, Jacques Martial, a citizen of the United States and a resident of the city, county, and State of New York, have invented a new, original, and ornamental Design for a Combined Storage and Dispensing Cabinet, of which the following is a specification, reference being had to the accompanying drawings, forming part thereof.

I claim:

The ornamental design for a combined storage and dispensing cabinet, substantially as shown.

JACQUES MARTIAL.
